LEVELING DEVICE FOR POOL AND BILLIARD TABLES

Filed March 25, 1931

Inventor
Franklin W. Young
By Attorney
Southgate, May - Newbury

UNITED STATES PATENT OFFICE

FRANKLIN W. YOUNG, OF WINCHENDON, MASSACHUSETTS, ASSIGNOR TO MASON & PARKER MANUFACTURING COMPANY, OF WINCHENDON, MASSACHUSETTS, A TRUST ASSOCIATION OF MASSACHUSETTS

LEVELING DEVICE FOR POOL AND BILLIARD TABLES

Application filed March 25, 1931. Serial No. 525,185.

This invention relates to tables used in the playing of pool and billiards, and relates more particularly to such tables as are of relatively light construction and intended for portable use. In such portable tables it is customary to form the bed or playing surface from a single continuous sheet of some composite or laminated material which is of no great thickness or rigidity. These portable tables are commonly used on floors or foundations which are not carefully leveled or prepared for such use.

Under these circumstances, it is very desirable to be able to straighten or level the playing bed of a pool or billiard table after the table has been placed on its more or less irregular foundation.

It is the general object of my invention to provide improved means for thus straightening or leveling the playing surface of a pool or billiard table.

To the accomplishment of this general object, I provide a plurality of actuating devices by the use of which selected areas of the table may be relatively raised or lowered as may be advisable.

My invention further relates to arrangements and combinations of parts which will be hereinafter described and more particularly pointed out in the appended claims.

A preferred form of the invention is shown in the drawings, in which

Fig. 1 is a plan view of my improved pool or billiard table;

Fig. 2 is a detail sectional elevation, taken along the line 2—2 in Fig. 1; and

Fig. 3 is a transverse sectional elevation, taken along the line 3—3 in Fig. 1.

Referring to the drawings, I have shown a light portable pool or billiard table comprising an enclosing frame 10 supported on legs 11 (Fig. 2) and having the sides thereof connected by cross frame members 12 loosely supporting the ends of the playing surface or bed 14. The lower inside edge of the frame is recessed and retaining strips 16 (Fig. 2) are secured to the frame 10 below the recess providing a deep groove to slidably receive the edges of the bed 14. The bed is thus somewhat loosely confined horizontally, so

that it may expand or contract laterally in the supporting frame-work.

The bed 14 may be made of any suitable composite or laminated material and is preferably formed from a single continuous sheet of limited thickness. In order to stiffen the bed 14, reenforcing bars 20 are secured in spaced relation to the under side of the bed 14 and are shown in the drawings as extending longitudinally thereof. While two such reenforcing bars are shown, it will be understood that additional bars may be added as desired, and also that the bars may be extended in length if preferred.

I not only provide for reenforcing the bed by the bars 20, but I also provide for straightening or leveling the bed, for which purpose cross braces 30 (Fig. 3) are inserted crosswise of the table underneath the bed 14 and bars 20, the ends of the braces 30 being firmly secured to the enclosing frame 10.

The upper surface of each brace 30 is cut away as indicated at 32 to clear the bed 14 and the clearance is increased toward the center of each brace as indicated at 33. Recesses 35 are provided for the bars 20.

Adjusting screws 40 are threaded in plates or nuts 41 fixed to the under side of the braces 30, and the screws extend upward through openings 42 in the braces. The screws 40 are provided with flattened wings 43 by which they may be conveniently grasped and turned.

The screws 40 are positioned at intersections of the braces 30 and reenforcing bars 20 and at their upper ends are provided with swivel plates 45 which are firmly secured to the under sides of the reenforcing bars 20, as by screws 46.

The ends of the adjusting screws 40 are preferably provided with reduced portions extending through the plates 45 and headed over to prevent axial displacement therefrom.

With this construction, it will be apparent that the braces 30 and bars 20 are held in definite spaced relation by the screws 40 at separated points in different areas of the bed 14. By turning a selected screw 40 in one direction or the other, the corresponding bed

area may be raised or lowered relative to the cross-brace 30 and in this manner the playing surface of the table may be straightened or brought to a desired level. Obviously the more cross bars and cross braces which are provided, the more intersections will be formed, and the number of adjusting screws 40 may be correspondingly increased.

Having thus described my invention and the advantages thereof, I do not wish to be limited to the details herein disclosed, otherwise than as set forth in the claims, but what I claim is:

1. A pool or billiard table comprising an enclosing frame, a bed having its edges supported in said frame, cross braces extending under said bed and secured at their ends to portions of said enclosing frame, and means on said cross braces for selectively raising or lowering said bed relative to said cross braces in a plurality of different areas.
2. A pool or billiard table comprising an enclosing frame, a bed having its edges supported in said frame, reinforcing bars secured in spaced relation to the under side of said bed, cross braces secured to said enclosing frame and extending across from side to side thereof and under said bed and reinforcing bars, and devices on said cross braces by which said braces and bars may be selectively separated or drawn together in a plurality of different selected areas of said bed.
3. A pool or billiard table comprising an enclosing frame, a bed having its edges slidably supported in said frame, cross braces extending under said bed and secured at their ends to portions of said enclosing frame, and a plurality of adjusting screws threaded to said cross braces and connected to said bed for movement of rotation only relative thereto, said screws being effective for selectively raising or lowering said bed relative to said cross braces in a plurality of different areas of said bed.
4. A pool or billiard table comprising an enclosing frame, a bed having its edges slidably supported in said frame, reinforcing bars secured in spaced relation to the under side of said bed, cross braces secured to said enclosing frame and extending across from side to side thereof and under said bed and reinforcing braces, a plurality of adjusting screws, nuts for said screws on said cross braces, and plates mounted for rotation on the ends of said screws but non-displaceable therefrom, said plates being secured to said reinforcing bars and said screws being effective to raise or lower portions of said bars and said bed relative to associated portions of said cross braces.

In testimony whereof I have hereunto affixed my signature.

FRANKLIN W. YOUNG.
